UNITED STATES PATENT OFFICE.

ELISHA A. POST, OF ALLEGAN, MICHIGAN.

MOLD FOR MAKING PAPER-BOARD BURIAL-CASKETS.

SPECIFICATION forming part of Letters Patent No. 708,075, dated September 2, 1902.

Application filed October 24, 1900. Serial No. 34,177. (No model.)

To all whom it may concern:

Be it known that I, ELISHA A. POST, a citizen of the United States, residing at Allegan, in the county of Allegan and State of Michigan, have invented certain new and useful Improvements in Molds for Making Paper-Board Burial-Caskets, of which the following is a full, clear, and exact description, reference being had therein to the accompanying 10 drawings, in which—

Figure 1 is a perspective view of the complete mold closed on a casket-body; Fig. 2, an end elevation thereof with the sides of the mold shown in dotted lines; Fig. 3, a vertical transverse sectional view through Fig. 1; Fig. 4, a plan view of a modified form of the mold, and Fig. 5 an end view of Fig. 4. Fig. 6 is a detail view of a slight modification.

This invention has relation to an apparatus for manufacturing that class of paper-board burial-caskets covered by my Patent No. 668,883, dated February 26, 1901; and the object of the invention is to provide a simple apparatus for shaping the blanks or 25 sheets of which the casket is constructed, as more fully hereinafter set forth.

The apparatus consists of a base-board *a*, shaped to correspond to the bottom or base of the casket, this base-board being provided 30 near each end with a vertical post *b*, threaded at its upper end and provided with a clamp-nut *c*. Hinged to each side of this base is one side *d* of the mold, the end sections *d'* of this side being curved and hinged so that 35 when the two sides are locked together in a vertical position the end sections conform to the curvature of the ends of the base and the ends of the casket. The end sections *d'* of the mold are connected detachably together 40 by any suitable means, preferably by means of flanges *e*, formed on the ends of the sections and connected by a bolt *f*.

Mounted upon the posts *b* is a core or plunger *g*, the posts passing up through openings in the core or plunger and the clamp-nuts *c* bearing upon the upper side of the core when the same is in position in the mold. This core or plunger is made slightly smaller all around than the interior of the mold, sufficiently to accommodate the walls of the casket *h*. Fastened to the upper side of the core or plunger is a pair of transverse bars *i*, whose

ends extend outward beyond the sides *d* (when the same are folded up) and are threaded for the reception of a crank-nut *j*. 55 The upper edges of the sides *d* are provided with upward-projecting plates or straps *k*, between the upper ends of which the threaded ends of the bars *i* project when the sides are folded up against the inclosed casket. 60 By means of these devices the hinged sides may be drawn tightly up against the inclosed casket and be held in place while the casket is drying and setting.

In the modification shown in Figs. 4 and 5 65 the end of the mold is shown polygonal in shape, each one of the sides or facets consisting of a separate plate having a separate hinge connection to the base-board, so that they may be closed up against the casket 70 separately. These end pieces are drawn and held tightly up against the end of the casket by any suitable means, preferably by means of suitable bolts *l*, swivelly connected to the top of the core or plunger and projecting outward over the top edges of the plates, each of the bolts being provided with a clamp-nut 75 which is adapted to engage a notched upward-extending plate or strap *m*, attached to the exterior of the section. 80

The casket is built up of laminæ of paper-board and hydraulic cement alternating with each other, and the blanks are preferably shaped as shown in my former patent, hereinbefore mentioned. In making caskets having thick walls the core or plunger is removed from its post and the sides of the mold folded down, as shown in dotted lines in Fig. 2. The blanks after having been properly coated with cement are then placed on the base-board, 90 each blank having been perforated to receive the posts or pins *b*. When sufficient blanks have been put in place to form the walls of the desired thickness, the core or plunger is placed on the pins or posts and clamped down 95 on the blanks. Then the blanks one by one are bent up and around the core or plunger, after which the sides of the mold are swung up and clamped by the bars *i* and their crank-nuts. Then the end portions of the blanks are folded in around the end of the core or plunger, 100 their abutting edges being properly adjusted. Then the hinged end sections *d'* are swung into place against the ends of the casket and

are securely clamped by their bolts *f*. The casket is then allowed to remain in the mold until it properly dries and hardens.

In making caskets which have comparatively thin walls the operation is as follows: The sides of the mold are clamped in place upon the base by the end bolts *f*. Then the blanks are placed upon or in the mold and are pressed down into the same by means of the core or plunger. Then the nuts *c* are screwed up tight, as likewise are the crank-nuts *j*. When the casket is removed from the mold, the perforations made for the passage of pins *b* are closed by suitable plugs and cement.

Instead of employing crank-nuts *j* to draw the sides up against the casket it is obvious that I may employ any other suitable devices—such, for instance, as a cam or eccentric device *n*, journaled in the projecting end of the bar *i* and bearing upon the washer *o*, which latter rests against the outer surface of the plates *m*.

It will be understood that the cover and the panels of the casket are to be made in substantially the same manner.

Having thus fully described my invention, what I claim, and desire to secure by Letters Patent, is—

1. A mold for making paper-board burial-caskets and the like, consisting of a base-

board, sides hinged thereto and adapted to be connected together at their ends, the posts rising from the base within the mold and threaded at their upper ends, a core or plunger fitting down over said posts and within the mold, and clamp-nuts on the upper ends of the posts, substantially as set forth.

2. A mold for forming laminated paper-board vessels, such as burial-caskets, a base provided with a pair of vertical posts, one rising from either end, a plunger or core fitting down over these posts and having its exterior shaped to conform to the interior of the casket, means for clamping the core or plunger down upon the base, hinged sides connected to the base and conforming to the exterior of the casket.

3. A mold for forming paper-board vessels, such as burial-caskets, comprised of a base, a pair of hinged sides, each of which is provided with a hinged section at each end, means for clamping the end sections together, and a removable core.

In testimony whereof I hereunto affix my signature, in the presence of two witnesses, this 22d day of October, 1900.

ELISHA A. POST.
